United States Patent

Des. 241,779

Patented Oct. 5, 1976

241,779

HAIR DRYER POWER UNIT OR SIMILAR ARTICLE

John C. Shalvoy, Fairfield, Conn., assignor to
General Electric Company

Filed Jan. 20, 1975, Ser. No. 542,521

Term of patent 7 years

Int. Cl. D28—03

U.S. Cl. D86—10 F

FIG. 1.

FIG. 2.

FIG. 3.

FIG. 4.

FIG. 1 is a perspective view of a hair dryer power unit showing my new design, the top coupling being rotated;

FIG. 2 is a top plan view thereof with the coupling in alternate position;

FIG. 3 is a right side elevational view thereof; and

FIG. 4 is a rear elevational view thereof.

I claim:

The ornamental design for a hair dryer power unit or similar article, substantially as shown.
